UNITED STATES PATENT OFFICE.

JAMES L. MAGINERNEY, OF GRAND RAPIDS, MICHIGAN.

MACHINE FOR PLACING SPRINGS IN FABRIC POCKETS.

Application filed May 9, 1927. Serial No. 190,118.

This invention relates to machines for making coiled springs and placing same in pockets of fabric strips.

One object of the invention is to co-ordinate a spring coiling device with mechanisms for filling fabric pockets with springs, and with spring fastening means, whereby a strip of fabric having a plurality of adjacent pocket sections may be rapidly filled with springs and the springs secured within the pockets.

Another object is to accomplish this result by mechanism which shall, practically speaking, be automatic as well as continuous in operation.

To the accomplishment of these objects, the invention consists in the devices and combinations of devices illustrated in the accompanying drawings and herein described; and more particularly pointed out in the subjoined claims.

These and other objects and advantages may be accomplished by means which may be generally described as follows:

A strip of suitable fabric, such for example as burlap, is fed continuously into and through the machine, being first folded longitudinally between its sides into U-shape, with the two laps superposed. The marginal portion of each lap is inturned. I prefer to use a plurality of fabric partition members secured, preferably, by stitching, in spaced apart relation to the top and bottom layers of the fabric strip, thus forming a plurality of pockets lengthwise of the strip.

Wire is fed continuously through a suitable coiling device, to form a helical or spiral spring, and as each spring is formed, the wire is severed, permitting the completed spring to pass into a funnel and then downwardly into a hollow frame to a reciprocating member which travels in the horizontal plane of the folded fabric strip. Each spring is compressed, while in the hollow frame, by a pair of compressor arms, the flanges of which are caused to enter the hollow frame or tube and engage the spring. The tube has diametrically opposite slots for this purpose, which permit the compressor arm flange to rest upon the severed, coiled spring and when the arm flanges are automatically caused to move downwardly through these slots, they push the spring through the tubular member and compress the spring so that the reciprocating member, which operates as soon as the spring is compressed and positioned opposite its end,

may push the compressed spring into the open or spread apart folds of the fabric strip.

A pair of pivoted jaws are closed upon the top and bottom layers of the fabric strip over the spring compressed therebetween, and move the fabric a predetermined distance, i. e., sufficiently to bring a pocket space into position to receive the next compressed spring. When these jaws are opened and returned to repeat this operation, the released spring will expand quickly, spreading apart the top and bottom layers of the fabric the proper distance,—a part of the top and bottom volutes of the spring at the same time entering the small pocket-recess formed between the inturned marginal parts of the fabric and the top and bottom layers, respectively, thereof.

As the fabric strip continues to be moved by the gripping jaws, through the machine, the part or pocket section thus filled with springs is passed over a conveyor through a pair of stapling devices, the first one passing a staple through the top of the strip to secure one end coil or volute of the spring to the fabric, and the second one stapling the other end coil or volute in the other pocket recess formed by the inturning of the other margin of the strip.

The various parts are synchronized so that the fabric may issue from the machine with substantially a step by step or intermittent movement, the completed strip having a plurality of pockets rectangular in form, open at one face, and having a coiled spring in each pocket held therein by the inturned fabric margin and by staples.

In the drawings:

Figure 1 is a side view of a machine embodying my invention.

Figure 2 is a top plan view of the same machine.

Figure 3 is a front elevation, partly in section, the section being in the transverse, vertical plane indicated by the dotted line 3—3 on Figures 1 and 2, and looking in the direction indicated by the arrow.

Figure 4 is a top plan view of certain of the parts shown in Figure 2, but on an enlarged scale.

Figure 5 is a sectional view, enlarged, the section being taken in the vertical plane indicated by the dotted line 5—5 on Figure 4.

Figure 6 is a transverse sectional view at one end of the machine, the section being

105

110

taken in the vertical plane indicated by the dotted line 6—6 on Figure 4, and likewise by the dotted line 6—6 of Figure 7.

Figure 7 is a sectional view of the same end 5 of the machine but taken at right angles to the section shown on Figure 6, the section being in the vertical plane indicated by the dotted line 7—7 on Figure 2.

Figure 8 is a top view, partially in section, taken in the plane indicated by the dotted line 8—8 of Figure 6 and looking downward as indicated by the arrows.

Figure 9 is a face view of the cam shown in Figure 7, looking at the cam in the direction indicated by the arrow.

Figures 10 and 11 are fragmentary views of parts illustrated in Figure 7, showing the gripping jaws in two positions.

Figure 12 is a fragmentary view looking 20 into the pocketed strip, showing distended springs in two of the pockets and the gripping jaws in the partially opened position to release the spring which had been held, compressed, in a pocket.

Figure 13 is a sectional view of the tube to receive the springs from the coiler as formed, the section being taken in the vertical plane indicated by the dotted line 13—13 on Figure 3.

Figures 14 and 15 are sectional views through the spring tube, showing two positions of the spring compressing arms, each section being taken in the vertical plane indicated by the dotted line 14—14 on Figure 13, 35 and looking in the direction indicated by the arrows.

Figure 16 is a transverse sectional view of the tube, the section being taken in the horizontal plane indicated by the dotted line 16—16 on Figure 14.

Figure 17 is a sectional view, enlarged, of a portion of one of the compressing arms, the section being taken in the vertical plane of the dotted line 17—17 on Figure 15.

Figure 18 is a sectional view of the parts shown in Figure 17, the section being taken in the plane of the dotted line 18—18 on Figure 17.

Figure 19 is an elevation showing a face 50 view of the cam illustrated in Fig. 2, looking into the direction indicated by the arrow 19 on Figure 2.

Figure 20 is a vertical, sectional view of one of the pockets of the fabric strip, shown 55 with a spring enclosed and stapled therein, the section being taken in the vertical plane indicated by the dotted line 20—20 on Figure 21.

Figure 21 is a plan or top view of the pocket shown on Figure 20.

Figure 22 is a fragmentary, sectional view of Figure 20, the section being taken in the vertical plane of the dotted line 22—22 on Figure 20.

The fabric strip.—The pocketed strip A

will be fed into one side of the machine in any convenient manner, as from a reel, or other source of supply, and will emerge from the other side of the machine with a spring in each pocket as shown in Figures 4 and 20. 70

The strip of fabric, such as burlap, or the like, indicated as a whole by the letter A, is moved in the direction indicated by the arrows in Figures 3 or 4. This strip is folded longitudinally, as at 1, into U-shape, to have 75 an upper layer or fold 2 and a lower layer or fold 3. The outer margins of the strip are folded as shown at 4 and 5 and form two longitudinally extending parts which are inwardly turned against the layers 2 and 3, respectively. When this strip is completed into pocketed form it will assume the appearance indicated on Figure 20. A portion of the top 80 layer 2 and a portion of the bottom layer 3 will constitute the top and bottom, respectively, of the pocket, and the folded portion 1 and the adjacent portions of the top and bottom layers 2 and 3, will constitute a back 6. Usually I prefer to separate the top and the

bottom layers 2 and 3 by transversely positioned, spaced apart, partition strips 7 of similar fabric, the ends of the partition 7 being secured to the top and bottom 2 and 3, respectively, by transverse lines of stitching or other suitable means. These partitions 7, 90 when used, will form the two sides of each pocket which, as shown, is a rectangularly shaped pocket having an open face. A spring S is positioned in each pocket, a part of the upper and lower volute or coil of the spring entering the space between the inturned portions 4 and 5 and the top and bottom portions 2 and 3, respectively, of the fabric, and being secured therein in any suitable manner, but preferably by means of staples 8. 100

The mechanism.—Referring now more particularly to Figures 1—2—3—4, the major portion of the mechanism illustrated is suitably mounted upon a frame B, having a base 9, and carrying in suitable bearings an operating shaft 10, which shaft is actuated by any suitable motive power, as for example from a belt 11 over pulleys 12 mounted upon the shaft 10. 105

The frame B is provided with a forwardly extending table 13, mounted upon which is a vertically extending tube T secured by a bracket 14. Removably positioned upon the upper end of the tube T is a curved, hollow funnel 15 adapted to receive a spring S. A 110 suitable spring coiler of any conventional type is designated as a whole by the letter C, said device being adapted to receive spring wire 16 from any source of supply and by means of a coiler head 17 convert the wire into a spring S in a familiar manner. The spring coiler C, per se, being no part of the present invention, except in combination as a whole with co-operating parts of the machine, need not be further described. When 115

the coiler head 17 has formed the spring S, the wire 16 is severed by a wire cutter 18 so that the spring S is free to fall through the funnel 15 downwardly into the tube T where 5 said spring is first arrested, then permitted to travel to the bottom of the tube, then compressed, then moved, by a plunger action, across the table 13 and into the fabric strip A, the folds 2 and 3 thereof having been separated, 10 as will be presently described, to permit the compressed spring to be entered between them.

Fabric fold spreader.—Mounted upon the end of the table 13 and extending within the 15 path of the moving folded fabric strip A, is a hollow spreader block 19 of an interior diameter sufficiently large to permit of the coiled spring S, when compressed, to be pushed therethrough. The two folds 2 and 20 3 of the oncoming fabric strip ride over the top and below the bottom of the spreader block 19, as will be understood by reference to Figures 3, 5 and 13. Extended at the front end of the machine beyond the table 13 is a 25 second table 20, supported upon a standard 21 which may rise from the base 9. On this table 20 and near the end of the table 13 is a vertically extending, supporting bracket 22 which carries and supports an inwardly 30 opening, U-shaped clip 23. The upper and lower layers 2 and 3 of the incoming strip A are fed between the arms of the clip 23 and, as before stated, over and under the spreader block 19. When the compressed spring S is 35 pushed into the folded fabric between the laps 2 and 3 thereof, the clip 23 holds the parts together against the expansion tension of the spring, as clearly shown on Figure 13. Two pairs of rotatable rolls 24, 25, having en- 40 gaging pins or teeth, located near either side of the spreader block 19, engage the folded fabric and hold it in proper position over the spreader block 19.

Spring compression.—Referring now 45 more particularly to Figures 13—14 and 15, it will be seen that the compression of the spring S is effected by the following mechanism: The tube T is provided with diametrically opposite, longitudinally disposed slots 50 26. On each side of the tube T and adjacent to said slots 26 is a rotatable shaft 27, each carrying a cam 28. On each side of the tube T, and in operative position to be engaged by the cams 28 are the arms 29, each pivoted at its upper end at 30 to a vertically movable bar 31, which moves in guides 31'. When the arms 31 are in their uppermost or raised position, the lower ends of the arms 29 are in the position shown on Figure 14, having been 55 forced into this position by the action of the cam 28, engaging lugs 32 on the outside of the arms 29. The lugs 32 on the arms 29, when in contact with the cam 28, function to quickly force the lower ends of the arms 29 into the slots 26, so that the spring S will be

held up and prevented from falling to the bottom of the tube T until the predetermined time. The lower portion of each arm 29 has a footpiece or flange 33 of a width sufficient to enter and to slide vertically through the 70 elongated slots 26 of tube T, and of a length sufficient to enter into the interior of the tube T when in the position shown in Figure 14, whereby the flanges 33 will engage a severed spring and hold it upwardly within the tube 75 T. When the shafts 27 rotate the cams 28 to a certain point and release the arms 29, and the bar 31 is moved downwardly (as herein-after explained), said arms 29 move downwardly also, and the flanges 33 thereon push 80 the next subjacent spring downwardly until said spring is in the compressed position shown in the bottom of the tube T on Figure 15. In said Figures 13, 14 and 15, the spring S, as formed and about to pass through the 85 funnel 15, is given a separate designation as S¹ and said spring will be held up in the upper part of the tube T by the flange 33 as indicated on Figure 14. The spring compressed is given the designation on Figure 15, 90 of S², and the spring next to be compressed is given the designation S³. In other words, when the spring S² is moved away the spring S³ is next compressed and the spring S¹ drops down into the position shown in the lower 95 part of Figures 14 and 15, and becomes spring S³.

Plunger movement.—Mounted in the upper part of the frame B, a rotatable shaft 34 carries a gear 35, the outer face of which is 100 provided with a cam 36. The short arm of a rocking lever 37 is in operative engagement with the cam 36, the lever 37 being fulcrumed at 38 to a supporting bracket 39 on the frame B. The longer arm of this lever 37 bears 105 against an antifriction roller 40 mounted at 41 in the end of a plunger rod 42, which latter is movably positioned upon the table 13. The lower part of the tube T is provided with diametrically positioned apertures 43 of sufficient size to permit the end of the plunger rod 42, when actuated, to pass through one aperture 43, contact with the compressed coiled spring S and push the latter bodily ahead of it through the other 110 opening 43 between the separated laps 2 and 3 of the fabric as before explained. The return movement of the plunger rod 42 is accomplished by the contraction of the spring 44 which at one end is operatively attached to the plunger rod, and at its other end is secured to a fixed support. The latter, in this instance, is shown as a bracket bar 45 secured to and rising from the frame base 9. It will be understood that the forward movement of the plunger places the spring 44 under sufficient tension to cause the prompt 115 return of the plunger to its normal position where its end will be ready to engage the spring next compressed in the tube T. 120

Gripping and feeding movement.—The feeding of the fabric strip through the machine is accomplished by step movement through a pair of gripping jaws, which take hold of the spring filled pocket and by bodily movement, transversely of the machine, carry the strip longitudinally a predetermined distance; i. e., a distance equal to the width of the pocket, so as to bring the folded, spread apart folds 2 and 3 of the fabric into the proper position for a compressed spring to be inserted therebetween. Then these jaws are opened, the fabric released, the jaws returned to their initial position, ready to grip the fabric containing the next adjacent spring to repeat the operation. The gripping jaws are positioned at one side of the clip 23, so as to take hold of the fabric strip with the compressed spring therein, and draw the strip out away from the clip 23.

Referring more particularly to Figures 10, 11 and 12, I will first describe the gripping devices, which consist of two vertically movable jaws 46, 46, spread apart and fulcrumed at 47, 47, upon a standard 48. Between these jaws is a spring 49, the action of which is normally to hold apart the gripping ends of the jaws 46. These ends 46 carry plates 50 sufficiently large in area to cover the spring of largest diameter that is to be used in making the strips. The under side of the plate 50 is provided with pins 51 adapted, when the arms 46 are closed, and the plates 50 embrace the folded spring-filled strip, to prevent the fabric from slipping between the plates and to carry the fabric with the plates and the jaws as the latter are moved bodily. The opposite ends of the gripping jaws 46 are spread apart and so shaped as to be operatively engaged by a plate 52 one end of which is wedge shaped, as indicated at 52¹, and mounted on the end of a reciprocating member 53. When the wedge 52¹ is inserted between the jaws 46, the tension of the spring 49 is overcome and the gripping plates 50, 50, are brought together. When the gripping jaws 46 are moved transversely of the machine, as hereinafter explained, the ends opposite the gripping ends ride over the wedge 52¹ and by the tension of the spring 49 are forced towards the flat plate 52, whereby the fabric strip and spring are released and the gripping jaws may be returned to their original position.

In Figures 10 and 12, the jaws 46 have started to open, the spring S held between the plates 50 has been partially released. In Figure 11 the jaws have entirely separated, the spring S has been expanded to completely fill the pocket and the mechanism is in position to be moved laterally to the left hand, as shown in Figure 12, so as to repeat the movement as above explained.

Referring now to Figure 7, the reciprocating member 53 is actuated by the movement

of the rocking arm 54, fulcrumed at 55 upon a bracket 56, which extends out from the table 20. A reciprocating arm 57 is held upon the under side of the table 20 by any convenient means, as for example, by a pair of downwardly projecting, spaced apart lugs 58 on the table 20, the bar 57 being held in position by a cover plate 59. This bar 57 carries on its short member 60 an adjusting screw 61 which latter engages one end of the rocking arm 54. The adjustment of the screw 61 enables me to determine to a nicety the amount of lateral movement to be given to the wedge 52 to open and close the jaws 46.

The inner end of the bar 57 is adapted to be engaged by the cam surface 62 on the face of the block 63, mounted upon a rotatable shaft 64.

When the block 63 is rotated, the cam 62 pushes the bar 57 so that the rocking arm 54 moves the wedges 52 inwardly against the tension of the springs 65.

The table 20 is provided with an upwardly extending member 66 which provides means for supporting and forms a seat for the reciprocating bar 53. One end of the springs 65 is attached at 67 to the member 66 and the other end of each spring is attached at 68 to the wedge 52 (Figure 4). It will be understood that when the rocking arm 54 moves the wedge forward, the springs 65 are stretched and put under tension, and when by the rotation of the cam block 63, the end of the arm 57 is disengaged from the cam surface 62, the springs 65 very promptly pull the wedge 52 from the position shown in Figure 10 to the position shown in Figure 11, thus the rocking arm 54 is reversed and the bar 57 returned so that its free end may be engaged by the cam 62 for the next succeeding cycle of motion.

The gripping jaws 46 and associated parts, however, have another movement, transversely of the machine, as stated, for the purpose of feeding the spring filled strip through the machine. This is accomplished by the following means: The standard 48 is secured to a plate 69 from which depends a pin 70. The plate 69 is held upon the table 20 by a pair of L-shaped guide bars 71, as clearly shown in Figures 4, 7, 10 and 11. The table 20 is provided with an aperture 72, through which the pin 70 extends, said pin being of sufficient length to enter a recess or cut away portion in the block 63 and to have its end engaged by and operated from the cam surface 73 which constitutes the bottom of the recess. It follows that when the shaft 64, carrying the block 63, is rotated, the cam surface 73 will move the pin 70 and therefore the plate 69 a distance sufficient to bring the gripping jaws 46 from the position shown in full lines to the position shown in dotted lines in Figure 6. The return movement from the dotted position to the full line position is accom-

plished by the contracting of the spring 74, which at one end is secured at 75 to the plate 69 and at its other end 76, is secured to any fixed support, in this instance the bracket 77.

6 Proper tension of the spring 74 will be obtained by having the engaging means at either end, 75 or 76, a hooked screw, which may be adjustably secured in and out as desired.

10 The opening 72 through the table 20 is elongated. Its longest dimension is transverse of the machine and is the direction of the reciprocating movement of the plate 69. In order to limit the extent of movement of the plate 69 in the guide ways 71, the adjusting screw 78 is mounted in a suitable aperture in the table 20, its end extending into the aperture 72 so as to be engaged by the pin 70 and thus limit the movement in one direction of the plate 69. This arrangement permits of adjustment so the gripping jaws will grasp a pocket and spring and move the strip a distance equal to the width of a pocket.

25 *Stapling mechanism.*—After the strip has been filled with springs, one in each pocket, the inturned edges 4 and 5 of the fabric and the springs S are suitably fastened together. This may be done by stitching or by using a hand stapling implement, but I prefer to use 30 conventional stapling machines such as are on the market and available for such purposes. Two of such machines are illustrated in Figure 4, and designated as a whole at 79, 80. The first stapler 79 is located so as to be 35 in the path of the strip with springs in the pockets, adapted to engage the upper lap 2 and the inturned margin 4 of the strip, and to insert the staple 8 therein as shown in Figure 22. The other stapling machine 80 is on the 40 opposite side of the strip A. In order to present the lower lap 3 to the machine 80, I locate the latter a sufficient distance from the stapler 79 to permit of twisting the strip half way round. This twisting takes place between the two stapler machines at the broken away part of the strip, as indicated in Figure 4. Such half-twist will present the lower lap 3 of the strip uppermost so that stapler 80 45 may operate thereon upon the inturned margin 5 and lap 3. The staplers may be actuated by any suitable mechanism. A double stapler, with its operating mechanism spaced apart the height of the strip, may be used in place of two staplers.

50 *Driving mechanism.*—Referring now to the mechanism for driving or transmitting motion to the various parts heretofore referred to, the spring compressor arms 29 are reciprocated by the following mechanism:—the belt 11 over pulley 12, mounted on shaft 10, driving the gear 81, which meshes with the pinion gear 82, through gear 83, and gear 84 on shaft 85. The driven shaft 85 carries a slotted crank lever 86, having an adjusting arm 87 adjustably secured in the slot by

means of a bolt and nut 88. The arm 87 is pivotally connected to a cross piece 89, which is connected at each end to one of the vertically movable bars 31 which travel in the guide ways 31¹. By this mechanism the compressor arms 29, pivotally connected to the movable bars 31, are given the reciprocating motion heretofore described.

60 The horizontally arranged shafts 27, which carry the cams 28, are driven by the following mechanism; a gear 90 on the shaft 10, meshing with gear 91, through gear 92, on shaft 93, said shaft carrying gear 94 in mesh with gear 95, through two idler gears 96 to gear 97, on shaft 27.

70 The plunger 42 is reciprocated in a horizontal plane, as heretofore explained, by the action of the cam 36 in operative connection with lever 37. This cam 36 on the gear 35 is rotated by the belt 11, over pulley 12, on shaft 10, carrying pinion gear 35¹, which meshes with the gear 35 on the shaft 34.

80 The shaft 64 is rotated through pinion gear 82, meshing with gear 83 on shaft 98, carrying a sprocket wheel 99, sprocket chain 100, 90 meshing with sprocket gear 101, on the stub shaft 102, through sprocket wheel 103, sprocket chain 104 to the sprocket wheel 105 mounted on the shaft 64.

90 *Conveyor*—The shaft 64 carries a sprocket gear 106, which, in turn, works sprocket chain 107 which meshes with sprocket gear 108 on shaft 109, mounted on a standard 109¹, rotating the pulley 110, which carries the conveyor belt 111. This conveyor belt carries 100 the spring strip to the stapling device heretofore described.

95 It will be manifest that the springs may be secured in the fabric pockets by means other than the stapling devices described. For instance, a sewing machine may be used for this purpose.

105 It will also be obvious that the machine may be used for placing springs in the pockets of a strip differing in construction from the particular strip herein described. As an example, I refer to a strip such as that shown in the Marshall Patent. No. 685,160.

110 Changes in the details of construction of the machine may be made without departing from the scope of the invention, and I do not desire to be limited to the details of construction herein shown and described, except as pointed out in the appended claims.

115 I claim as my invention:

120 1. A machine for placing coiled springs in fabric, pockets, comprising mechanism for compressing the springs, means for maintaining the springs in compressed condition, a reciprocating plunger for moving the compressed spring in a horizontal plane toward and between the two laps of a folded fabric strip, a support for the fabric strip, a pair of gripping jaws, adapted to grasp the fabric strip and spring therebetween, means for 125 130

transmitting limited reciprocating movement transversely of the machine to said jaws, means for releasing the gripping jaws from the strip, and means for returning the jaws to original position.

2. A machine for placing coiled springs in fabric pockets, comprising mechanism for compressing the springs, means for maintaining the springs in compressed condition, a reciprocating plunger for moving the compressed spring toward and between the two laps of a folded fabric strip, a support for the fabric strip, means adapted to grasp the fabric strip and spring therebetween, means for transmitting limited reciprocating movement to said grasping means, means for releasing the grasping means from the strip, and means for returning the grasping means to original position.

3. A machine for placing coiled springs in fabric pockets, comprising mechanism for compressing the springs, means for maintaining the springs in compressed condition, a reciprocating plunger for moving the compressed spring in a horizontal plane, mechanism for reciprocating the plunger, a support for the fabric strip, a pair of gripping jaws having a limited reciprocating movement transversely of the machine, mechanism for reciprocating the gripping jaws, and mechanism for opening and closing the gripping jaws, said mechanism for compressing the springs, the plunger reciprocating mechanism, said jaw reciprocating mechanism and said jaw opening and closing mechanism being operatively connected so as to function synchronously.

4. A machine for placing coiled springs in fabric pockets, comprising mechanism for compressing the springs, means for maintaining the springs in compressed condition, a reciprocating plunger for moving the compressed spring in a horizontal plane toward and between the two laps of a folded fabric strip, a support for the fabric strip, a pair of fulcrumed gripping jaws located adjacent the fabric support and normally separated from each other at their gripping ends, means for forcing the jaws toward each other to grasp the fabric and spring, means for moving the jaws while in closed position transversely of the machine for a limited distance, means for releasing the gripping jaws from the fabric strip, and means for moving the jaws transversely to their original position.

5. A machine for placing coiled springs in fabric pockets, comprising mechanism for compressing the springs, means for maintaining the springs in compressed condition, a reciprocating plunger for moving the compressed spring in a horizontal plane toward and between the two laps of a folded fabric strip, a support for the fabric strip, a pair of gripping jaws fulcrumed between their ends, a movable support for same, the grip-

ping ends of the jaws being normally held apart from each other, a reciprocating wedge member adapted to force the gripping jaws toward each other, mechanism for moving the gripping jaw support a limited distance transversely of the machine and over said wedge member, means for withdrawing the wedge member and means for moving the gripping jaws and support transversely back to their original position.

6. A machine for placing coiled springs in fabric pockets, comprising mechanism for compressing the springs, means for maintaining the springs in compressed condition, a reciprocating plunger for moving the compressed spring in a horizontal plane toward and between the two laps of a folded fabric strip, a support for the fabric strip, a pair of gripping jaws, means for transmitting limited reciprocating movement transversely of the machine to said jaws, the jaws being adapted to grasp the fabric strip and spring therebetween and carry the same a distance equal to the width of a spring pocket, means for releasing the gripping jaws from the strip and means for returning the jaws to original position, the means for reciprocating the gripping jaws transversely of the machine comprising a support for the jaws and a cam, mounted upon a rotatable shaft and contacting with said support, and a tension spring for returning the gripping jaw support to its original position when the cam has moved out of contact with said support.

7. A machine for placing coiled springs in fabric pockets, comprising mechanism for compressing the springs, means for maintaining the springs in compressed condition, a reciprocating plunger for moving the compressed spring in a horizontal plane toward and between the two laps of a folded fabric strip, a support for the fabric strip, a pair of reciprocating gripping jaws fulcrumed upon a support, the gripping ends being normally separated from each other by a tension spring, a reciprocating wedge plate adapted to force the gripping jaws toward each other, means for reciprocating the wedge plate comprising a cam mounted upon a rotatable shaft, a horizontally disposed bar, and a rock lever, a support therefor, said rock lever being in operative engagement with said horizontal bar and with the wedge plate, and a tension spring for returning the wedge to its nonengaging position.

8. A machine for placing coiled springs in fabric pockets, comprising mechanism for compressing the springs, means for maintaining the springs in compressed condition, a reciprocating plunger for moving the compressed spring in a horizontal plane toward and between the two laps of a folded fabric strip, a support for the fabric strip, a pair of gripping jaws fulcrumed upon a standard, a movable plate connected therewith, a

fixed support, guide bars upon the fixed support, a pin depending from said movable plate and extending through an aperture in the fixed support, mechanism for reciprocating the movable plate in operative engagement with the depending pin.

9. A machine for placing coiled springs in fabric pockets, comprising mechanism for compressing the springs, means for maintaining the springs in compressed condition, a reciprocating plunger for moving the compressed spring in a horizontal plane toward and between the two laps of a folded fabric strip, a support for the fabric strip, a pair of gripping jaws fulcrumed upon a standard, a movable plate connected therewith, a fixed support, guide bars upon the fixed support, a pin depending from said movable plate and extending through an aperture in the fixed support, mechanism for reciprocating the movable plate in operative engagement with the depending pin, and an adjusting screw, mounted on the fixed support for limiting the movement in one direction of the movable plate.

10. A machine for filling fabric pockets with springs, means for compressing the spring and for maintaining same in compressed condition, a horizontally disposed, reciprocating plunger for moving a compressed spring toward and between the laps of a folded fabric strip, a support for the fabric strip, gripping jaws normally spread apart, mechanism for forcing the gripping jaws toward each other, said jaws being fulcrumed between their ends and mounted upon a movable support, and mechanism for reciprocating the movable support, the mechanism for forcing the jaws toward each other comprising a wedge, a rock arm, a horizontal bar and a cam faced block mounted on a rotatable driven shaft, and the mechanism for reciprocating the movable support for the gripping jaws comprising a second cam surface on said block, a pin depending from the movable support in operative engagement with said cam.

11. A machine for filling fabric pockets with springs, means for compressing the spring and for maintaining same in compressed condition, a horizontally disposed, reciprocating plunger for moving a compressed spring toward and between the laps of a folded fabric strip, a support for the fabric strip, gripping jaws normally spread apart, mechanism for forcing the gripping jaws toward each other, said jaws being fulcrumed between their ends and mounted upon a movable support, and mechanism for reciprocating the movable support, the mechanism for forcing the jaws toward each other comprising a wedge, a rock arm, a horizontal bar and a cam faced block mounted on a rotatable driven shaft, and the mechanism for reciprocating the movable support for the gripping

jaws comprising a second cam surface on said block, a pin depending from the movable support in operative engagement with said cam, and adjusting screws carried by the fixed support for limiting the transverse movement of the gripping jaw support and for adjusting the wedge movement.

12. A machine for placing coiled springs in fabric pockets, comprising mechanism for compressing the springs, means for maintaining the springs in compressed condition, a reciprocating plunger for moving the compressed spring in a horizontal plane toward and between the two laps of a folded fabric strip, a support for the fabric strip, a pair of gripping jaws fulcrumed upon a standard, a movable support therefor, a pin depending from the support, an apertured table, said pin projecting through said apertured table, guide bars beneath the table, a reciprocating bar mounted in said guide bars, a wedge mounted upon said table, a rock lever arm on said table in operative connection with the said horizontal bar and said wedge, and a recessed block mounted upon a rotatable shaft and having cam surfaces for operative engagement with the depending pin and with the reciprocating horizontal bar.

13. A machine for filling fabric pockets with springs comprising means for compressing the springs and for maintaining the springs in compressed condition, a horizontally disposed reciprocating plunger bar, a U-shaped housing located with its open side opposite the end of the reciprocating plunger, a folded fabric strip in the housing, a pair of gripping jaws, a movable support for the jaws, near one end of the U-shaped housing, said jaws having limited movement away from and toward said housing.

14. A machine for filling fabric pockets with springs, comprising means for compressing the springs and for maintaining the springs in compressed condition, a horizontally disposed reciprocating plunger bar, a spreader for separating the laps of a folded fabric strip, a pair of rotatably mounted, toothed rolls at one side of the spreader means, a U-shaped housing for the fabric strip, a fixed support, a pair of gripping jaws mounted upon a movable plate on said support near said U-shaped housing, and operative mechanism for transmitting reciprocating motion, transversely of the machine, to said gripping jaws.

15. A machine for filling fabric pockets with springs, comprising means for compressing the springs and for maintaining the springs in compressed condition, a horizontally disposed reciprocating plunger bar, a spreader for separating the laps of a folded fabric strip, a pair of rotatably mounted, toothed rolls at one side of the spreader means, a U-shaped housing for the fabric strip, a fixed support, a pair of gripping jaws mount-

ed upon a movable plate on said support near said U-shaped housing, means located on the fixed support for closing and opening the gripping jaws, and operative mechanism for transmitting reciprocating motion, transversely of the machine, to said gripping jaws.

16. In a machine for filling fabric pockets with springs, a slotted holder for the springs, means for compressing the springs in the holder, a horizontally disposed reciprocating plunger for moving the compressed springs, mechanism for operating plunger, a support for a folded fabric strip, a pair of gripping jaws movably mounted on the support, mechanism for transmitting reciprocating motion to the gripping jaws transversely of the machine, means for opening and closing the gripping jaws, and mechanism for operating same.

17. In a machine for filling fabric pockets with springs, a slotted holder for the springs, means for compressing the springs in the holder, a horizontally disposed reciprocating plunger for moving the compressed springs, mechanism for operating plunger, a support for a folded fabric strip, a pair of gripping jaws movably mounted on the support, mechanism for transmitting reciprocating motion to the gripping jaws transversely of the machine, means for opening and closing the gripping jaws, means for compressing the spring comprising a pair of pivotally mounted arms provided with flanges adapted to enter the slots of the tubular holder, mechanism for reciprocating the pivoted arms and means for forcing the arm flanges into the holder.

18. In a machine for filling fabric pockets with springs, a slotted holder for the springs, means for compressing the springs in the holder, a horizontally disposed reciprocating plunger for moving the compressed springs, mechanism for operating plunger, a support for a folded fabric strip, a pair of gripping jaws movably mounted on the support, mechanism for transmitting reciprocating motion to the gripping jaws transversely of the machine, means for opening and closing the gripping jaws, means for compressing the springs comprising a pair of pivotally mounted arms provided with flanges adapted to enter the slots of the tubular holder, mechanism for reciprocating the pivoted arms and means for forcing the arm flanges into the holder, said means comprising cams mounted upon rotatable shafts.

19. In a machine for filling fabric pockets with springs, a slotted holder for the springs, means for compressing the springs in the holder, a horizontally disposed reciprocating plunger for moving the compressed springs, mechanism for operating plunger, a support for a folded fabric strip, a pair of gripping jaws movably mounted on the support, mechanism for transmitting reciprocating motion to the gripping jaws transversely of the ma-

chine, means for opening and closing the gripping jaws, and mechanism for operating the same, said mechanism for compressing the springs comprising a pair of pivoted arms with flanges thereon adapted to enter the slots in the holder, a pair of guide ways, vertically movable bars in the guide ways connected with said compressor arms, a cross piece connecting the movable bars, an adjusting arm secured at one end to the cross piece, a slotted crank lever secured to the other end of the adjusting arm, mechanism for actuating the crank lever, and means for forcing the compressor arms into the slotted tubular holder.

20. In a machine for filling fabric pockets with springs, a slotted holder for the springs, means for compressing the springs in the holder, a horizontally disposed reciprocating plunger for moving the compressed springs, mechanism for operating plunger, a support for a folded fabric strip, a pair of gripping jaws movably mounted on the support, mechanism for transmitting reciprocating motion to the gripping jaws transversely of the machine, means for opening and closing the gripping jaws, means for compressing the springs comprising a pair of pivotally mounted arms provided with flanges adapted to enter the slots of the tubular holder, mechanism for reciprocating the pivoted arms and means for forcing the arm flanges into the holder, said means comprising cams mounted upon rotatable shafts and lugs on the compressor arms.

21. In a machine for filling fabric pockets with springs, a slotted holder for the springs, means for compressing the springs in the holder, a horizontally disposed reciprocating plunger for moving the compressed springs, mechanism for operating plunger, a support for a folded fabric strip, a pair of gripping jaws movably mounted on the support, mechanism for transmitting reciprocating motion to the gripping jaws transversely of the machine, means for opening and closing the gripping jaws, and mechanism for operating same, the mechanism for operating the plunger comprising a driving shaft, a pinion mounted thereon, a cam gear in mesh with the pinion, a rock lever mounted upon a support, one end of the rock lever being in operative engagement with the cam and the other end with the reciprocating plunger.

22. In a machine for filling fabric pockets with springs, a slotted holder for the springs, means for compressing the springs in the holder, a horizontally disposed reciprocating plunger for moving the compressed springs, mechanism for operating plunger, a support for a folded fabric strip, a pair of gripping jaws movably mounted on the support, mechanism for transmitting reciprocating motion to the gripping jaws transversely of the machine, means for opening and closing the grip-

ping jaws, and mechanism for operating same, the mechanism for operating the plunger comprising a driving shaft, a pinion mounted thereon, a cam gear in mesh with the pinion, 5 a rock lever mounted upon a support, a roller on one end of the plunger, one end of the rock lever being in operative engagement with the

cam and the other end with the roller on the reciprocating plunger.

In testimony that I claim the foregoing as 10 my invention I affix my signature this 3d day of May, 1927.

JAMES L. MacINERNEY.
